UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

Application filed May 8, 1922. Serial No. 559,119.

To all whom it may concern:

Be it known that I, JOHN H. BARR, citizen of the United States; and resident of the borough of Manhattan, city of New York, 5 in the county of New York and State of New York, have invented certain new and useful Improvements in Typewriting Machines, of which the following is a specification.

10 My invention relates to typewriting machines, and more particularly to the frame of the machine and the manner of supporting various parts thereon.

The invention is directed more particularly to so-called portable machines, wherein it is desirable to make the parts as light in weight as is consistent with the rigidity and strength required to withstand the strains to which the machine may be subjected in 20 use and during transportation.

One of the main objects of my invention is to provide a simple, strong, light and effective frame for the machine, which aids materially in accomplishing the above mentioned results, and yet presents a pleasing outline and appearance; all unsightly parts being covered.

A further object of my invention is to provide a machine frame of the character 30 specified which comprises a double frame or two sections detachably but fixedly united, and in which all of the working parts of the machine may be supported by the inner frame or section, and the latter, together 35 with said parts, may then be introduced as a single unit into the outer enclosing frame or section, and be enclosed thereby and the sections firmly secured together.

This enables the working parts of the 40 machine to be assembled and mounted on the inner frame with facility, since the various parts of the machine are readily accessible when it is not enclosed in the outer frame. Moreover, there is no danger of marring the 45 finish of the outer frame since it is unnecessary to handle it until the machine is completely assembled and adjusted and ready to be introduced as a unit into the outer frame and thus delivered as a marketable machine.

50 To the above and other ends which will hereinafter appear, my invention consists in the features of construction, arrangements of parts and combinations of devices set forth in the following description and par-

ticularly pointed out in the appended 55 claims.

In the accompanying drawings wherein like reference characters indicate corresponding parts in the different views.

Figure 1 is a detail perspective view of 60 the sheet metal outer frame or section, shown detached.

Figure 2 is a detail fragmentary sectional view showing the manner of connecting the inner and outer frames at the sides thereof, 65 and of securing the top plate in place.

Figure 3 is a detail fore and aft vertical sectional view of the top plate.

Figure 4 is a detail perspective view of the inner frame or section, shown detached. 70

Figure 5 is a detail top plan view of the top plate.

Figure 6 is a detail bottom plan view of the top plate, shown on a larger scale.

Figure 7 is a vertical fore and aft sectional view of the machine, with the outer frame removed. 75

I have shown my invention in the present instance embodied in a Remington portable machine, many features of which are like, 80 or somewhat like those disclosed in the following patents and pending applications, viz:—A. W. Smith, Pat. 1,342,513, dated June 8, 1920; J. B. Holden, Pat. 1,386,256, dated Aug. 2, 1921; J. B. Holden, Pat. 1, 847,632, dated July 27, 1920; J. B. Holden, Pat. 1,381,994, dated June 21, 1921; J. B. Holden, Pat. 1,397,166, dated Nov. 15, 1921; H. E. Bridgwater, Pat. 1,388,164, dated Aug. 23, 1921; J. B. Holden, Sr. No. 547, 85 128, filed Mch. 27, 1922; G. A. Seib, Sr. No. 529,415, filed Jan. 16, 1922; J. B. Holden, Sr. No. 469,458, filed May 14, 1921; J. B. Holden, Sr. No. 585,951, May 6, 1922. It should be understood however, that the invention 90 may be embodied in other styles of machines.

I have represented in the drawings only so much of the Remington portable machine as is necessary to arrive at an understanding of my invention in its embodiment therein. 100

The frame of the machine comprises, in the main, what may be referred to as two members or sections, one of which is shown in detail in Fig. 4, and which may be termed the inner frame or section which supports all of the working parts of the machine, as will hereinafter appear. The other member may be called the outer sec- 105

tion or frame, and is shown in detail in Fig. 1. This outer frame encloses the inner frame and is detachably fixed thereto, obscuring a view of the inner frame 5 and many of the working parts of the machine, and imparting a neat and finished appearance to the machine as a whole. A top plate, shown in detail in Figs. 5 and 6, surmounts the outer and inner frames and 10 is detachably secured in place thereon.

The inner frame is designated as a whole by the reference numeral 1, and comprises two sheet metal side plates 2, and a hollow sheet metal cross bar 3 fixed at its ends on 15 studs that project from plates 4, which in turn are secured at 5 to the side plates 2. The side plates 2 may be further connected by a front comb plate 6, secured by screws 7 to inwardly extending ears 8 which project from the side plates 2. An angular sheet metal keeper bar 5^a may also be employed to connect the side plates; the upper screws 7 being employed to connect the keeper bar therewith. Forming a further firm connection 20 between the side plates 2 is a casting, designated as a whole by the reference numeral 9. This casting is formed with two bracket arms 10 each of which terminates in a foot piece 11. Each foot piece has an outwardly extending horizontally disposed rib or lug 12 that is seated in a horizontal milled slot 13 in the companion side plate 2 of the frame. The outer contact face 14 of each foot piece bears against a side plate 2, and 25 the casting is firmly secured to the side plates by headed screws 15 received at their threaded ends in the foot pieces 11 of the brackets 10. This casting includes a slotted type bar segment 16 and an integral slotted 30 segment 17 for the sub-levers of the type actions. In Fig. 4 I have shown only a few of the slots 18 and 19 in the two segments 16 and 17 respectively; the remaining slots being omitted to simplify the showing. It 35 will be understood that aside from other connections, the casting 9 constitutes a firm and rigid connection between the side plates 2 near the rear of the frame, whereas the cross bar 3 forms a further rigid connection 40 between the side plates near the front of the frame.

Various openings are provided in the side plates 2, as shown, for forming bearings for different working parts of the machine, for 45 mounting pivot pins on the side plates, for affording passage of the stems of connecting screws through the plates, and for various other purposes, but it will be unnecessary to describe these openings in detail or the purpose of each.

The lower edge of each side plate 2 is formed with feet 20 by which they may receive a support on the outer frame, as will hereinafter appear. Projecting rearwardly 50 from each side plate 2, near the lower por-

tion thereof, is a horizontally disposed extension 21 which, with the rear edge 22 of the main body portion of the plate, forms substantially a right angle, so as to provide an L-shaped recess in which the carriage support and carriage are received, and through which the carriage may travel, as will be understood from an inspection of Fig. 7.

From a consideration of the last mentioned figure, it will be understood that every working part of the machine is mounted on or supported by the inner frame; such parts being disclosed and described in detail in many of the hereinbefore mentioned patents 75 and pending applications. Thus the collapsing type bars and type actions are disclosed in the Smith Patent No. 1,342,513; the carriage, carriage mounting and case shifting mechanism in the Holden Patent No. 1,386,256; the escapement mechanism in the Seib application Sr. No. 529,415 and in the Holden application Sr. No. 558,951; the ribbon mechanism in the Holden Patent No. 1,397,166; the back spacing mechanism in 80 the Bridgwater Patent No. 1,388,164; and the line lock and margin stop mechanism is similar in many respects to the construction disclosed in the Holden Patent No. 1,381,994. 85

It is considered unnecessary therefore to 90 describe in detail all of these constructions, or so much of them as are shown in Fig. 7, it being deemed sufficient to refer briefly to these various constructions and to indicate that they are carried by the inner frame 1, 95 as shown in Fig. 7. This is especially true since such features are embodied in the Remington portable machine.

The key controlled type bars 23 are mounted in the slots 18 in the segment 16, 100 whereas the sub-levers 24 are mounted in the slots 19 in the segment 17. The key levers 25 are pivoted at their rear ends on the pivot rod 26 supported by a guide comb 27 fixed to the casting 9. The front end portions of the 110 key levers extend through the guide slots of the front guide comb 6.

The cast aluminum carriage support 28 carries sheet metal guide rails 29 and 30 which receive crossed bearing rollers 31 in 115 the ways therein. These rollers are also received in companion ways formed in the sheet metal bed plate 32 of the carriage on which is mounted a platen 33. The carriage moves across the machine over the projections 21 on the side plates 2, and through the L-shaped recesses therein, as hereinbefore explained. The carriage support is pivoted on two upright parallel arms 34 which project from a rock shaft 35, said shaft being 120 mounted at its reduced ends in openings 36 (see Fig. 4) in the side plates 2 of the frame. The carriage support 28 is fixed to two sheet metal plates 37 arranged at opposite sides of the machine near the plates 2 and which, 125

130

with the carriage support, constitutes the case shift frame on which the carriage is supported for bodily movement therewith fore and aft of the machine. The forward 5 end of each plate 37 is pivoted, as at 38, to a depending link 39, pivoted at its upper end on a pivot pin 40 that projects inwardly from the associated side plate 2 of the frame. In this manner the case shift frame is supported at its forward end by the parallel 10 links 39 and is supported at its rear end by the parallel arms 34.

Not only is the carriage shiftable with the case shift frame, but among other devices 15 that are also shiftable with said frame are the feed rack 41, the margin and line lock stops 42, the dog rocker 43, the universal bar 44, the frame 45 to which the universal bar is connected, the ribbon vibrator 46, its actuating arm 46^a, the ribbon spools 47, the ribbon feed mechanism including the ratchet wheel 48, the ribbon feed pawl 49, its actuating arm 50, the actuating arm 51 for the dog rocker, the rack 52 for the back spacer, 20 and the back spacer actuating rod 53.

The case shift frame may be shifted by any suitable means, those shown comprising a shifting lever 54 to which a link 55 is connected. The upper end of said link is pivoted to a bell crank lever 56, pivoted at 57 (see Fig. 4) on a stud projecting from the left-hand side plate 2 of the frame, and held in place thereon by a screw 58. A depending arm 59 on its bell crank lever co-acts 30 with the projection on the shift frame to shift it rearwardly to the upper case position. The parts may be locked in shifted position by a shift lock key 60 that controls a shift lock member 60^a mounted on the 35 front of the comb plate 6.

The space key 61 has its supporting levers 61^a fulcrumed on the comb plate 6 and extending rearwardly and down therefrom and connecting at their lower ends with a 40 squared cross bar 62. This bar carries an arm 63 operatively connected with a link 64 pivoted at its lower end to an actuating arm which forms part of the dog rocker.

It will be seen, therefore, that every working 50 part of the machine is carried by the inner frame, and that the construction is such that all of said parts may be assembled, mounted in place, and adjusted in said frame while it is detached from the outer frame. 55 The inner frame with the parts mounted thereon may then be introduced into the outer frame as a single unit without dismantling any part of the machine, and without having had occasion to handle or mar the 60 outer frame until the inner frame with the working parts thereon, is to be placed in position therein and the machine as a whole is ready to be delivered as a finished product.

The outer frame is preferably made of 65 thin sheet metal such as steel and is very

light since the strain on the machine is borne in the main by the inner frame. The main purpose of the outer frame is to cover many of the working parts and the unfinished inner frame, and impart to the machine a finished appearance and outline. Although the outer frame is light in weight, it adds, nevertheless, as a strengthening factor to the machine as a whole when secured in place with the top plate added. These parts tend to 70 strengthen and render more rigid the inner frame, and the machine as a whole, as will hereinafter appear. The outer frame, which is shown in detail in Fig. 1 and designated as a whole by the reference numeral 65, is made of two separate members welded together along the base at both sides and at the front, to form in effect one part. The lower member is formed from a single piece of metal of rectangular formation, as viewed 75 from above, with an inwardly directed flange 66 joined to an upwardly extending surrounding wall 67. Each front, back and side wall of this member is therefore angular, or substantially L-shaped in cross section. The 80 inwardly extending flange 66 is apertured at its four corners to receive rubber feet 68, as fully disclosed in the hereinbefore mentioned application Sr. No. 469,458, and by 85 which the machine is supported on its base-board. The other member of the frame section is formed from a continuous piece of sheet metal with a front cross piece or wall 69 and side walls 70. The body portion of 90 each side wall has a rearwardly extending portion 70^a near its lower edge corresponding substantially to the projections 21 on the inner frame and, like the latter, forming an L-shaped or angular recess through which the carriage may travel. Beginning at the 95 top edge 70^b, and at or about the point where the comb plate 6 of the inner frame is situated when the parts are assembled, each side plate 70 slopes downwardly and forwardly 100 at 71 to the front wall 69. An integral, inwardly turned flange, beading or rib 72 is formed on each inclined edge and continues 105 along the upper edge of the wall 69. This flange gives a finish to the frame and strengthens and renders it more rigid. In 110 order that the side walls of the outer frame may bear against the outer sides of the plates 2 of the inner frame at the points where the two frames are secured together, I prefer to form integral, inwardly extending bearing lugs 73 and 74 on the side walls 115 70 and 67, respectively, of the outer frame members, thus maintaining the side-walls of the inner and outer frame sections spaced apart except at the points where they are 120 rigidly connected together, as indicated in Fig. 2.

The flange 66, where it extends across the machine at the front thereof, carries a sheet metal bracket 75, fixed thereto at 76. This 125 130

5 bracket carries two felt pads 77 on the arms thereof, said pads co-acting with the space key 61 and with inwardly turned bracket arms 78 (see Fig. 7) to limit the movement of the space key in both directions.

10 The feet 20 of the inner frame are supported on the side members of the flange 66 when the inner frame is introduced in position in the outer frame. Headed screws 15 pass through openings 79, 80 and 81 in the sides of the outer frame and secure the two frame sections together. The screws which pass through the openings 81 also extend through registering openings 81^a in the side plates 2 of the inner frame, and are received in tapped openings in a cross bar 82. The screws which pass into the openings 79 are received in tapped openings 83 in the plates 2, whereas the screws 84 (see 20 Fig. 2) which pass through the openings 80, also pass through registering openings 85 in the plates 2 and are threaded in the tapped openings in depending lugs 86 on the top plate 87. These lugs are arranged between 25 and support the plates 2 against inward movement. In this manner not only are the inner and outer frames firmly secured together, but the top plate 87 is detachably secured on the machine, thereby 30 materially strengthening and rendering it more rigid.

The top plate may be of sheet metal but I prefer to make it of cast aluminum with depending strengthening ribs 88 formed thereon and a rearwardly and downwardly inclined curved portion 89 which may, if desired, be sheathed with a felt pad (not shown) to form a type rest for the ends of the type bars. The top plate is also provided with a downwardly and forwardly inclined flange or apron 90 that aids in obscuring the parts of the machine.

40 The machine when complete presents a neat and finished appearance with graceful outlines, and many of the working parts and the inner frame are covered by the outer frame and top plate.

45 What I claim as new and desire to secure by Letters Patent, is:—

50 1. In a typewriting machine, the combination of an inner sheet metal frame on which working parts of the machine are supported, and an outer surrounding sheet metal frame detachably fixed to said inner frame, said outer frame comprising two sheet metal members fixedly united and each formed from a single piece of sheet metal, one member being in the nature of a rectangular frame substantially L-shaped in 55 cross section, and the second member being outside of the first mentioned member and surrounding it on three sides.

60 2. A frame for a typewriting machine comprising an outer part having a front and two side members formed as one continu-

ous piece and open at the rear, and a second rectangular open part secured to said first mentioned part and substantially L-shaped in cross section to provide an inwardly extending flange on all four sides.

70

3. A frame for a typewriting machine comprising an outer sheet metal part having a front and two side members formed as one continuous piece and open at the rear, the side members sloping downwardly and forwardly to the front member from points to the rear of the keyboard, said sloping portions of the sides and the front member having an inwardly turned flange, and a second rectangular open sheet metal part 80 secured in said first mentioned part and substantially L-shaped in cross section to provide an inwardly extending flange on all four sides.

80

4. A frame for a typewriting machine comprising an outer sheet metal part having a front and two side members formed as one continuous piece and open at the rear, the side members sloping downwardly and forwardly to the front member from points to the rear of the keyboard, said sloping portions of the sides and the front member having an inwardly turned flange, and a second rectangular open sheet metal part 90 secured in said first mentioned part and substantially L-shaped in cross section to provide an inwardly extending flange on all four sides, and a top plate surmounting and detachably connected to said first named part.

90

5. A frame for a typewriting machine comprising an outer sheet metal part having a front and two side members formed as one continuous piece and open at the rear, the side members sloping downwardly and forwardly to the front member from points to the rear of the keyboard, said sloping portions of the sides and the front member having an inwardly turned flange, a second rectangular open sheet metal part secured 100 in said first mentioned part and substantially L-shaped in cross section to provide an inwardly extending flange on all four sides, and a top plate which extends over the two side members of the first mentioned part 105 and is detachably secured thereto.

105

6. The combination of an inner sheet metal frame, an outer sheet metal frame fixed thereto, a top plate, and means for detachably connecting the latter to said inner 110 and outer frames and effective to stiffen them.

110

7. In a typewriting machine, the combination of a system of type actions, a carriage, an inner sheet metal frame on which 125 said system of type actions and carriage are supported in their entirety, and an outer sheet metal frame enclosing the inner frame and detachably fixed thereto and into which the inner frame with the parts supported 130

115

120

125

130

- thereby may be introduced as a single unit and from which it may be so detached.
8. In a typewriting machine, the combination of a system of type actions, a carriage, 5 a case shift frame therefor, an inner sheet metal frame on which said system of type actions, the carriage and case shift frame are supported in their entirety, and an outer sheet metal frame enclosing the inner 10 frame and detachably fixed thereto and into which the inner frame with the parts supported thereby may be introduced as a single unit and from which it may be so detached.
- 15 9. In a typewriting machine, the combination of a system of type actions, a carriage, a case shift frame therefor, carriage escapement mechanism, an inner frame by which the hereinbefore mentioned parts are supported, and an outer frame enclosing said 20 inner frame and detachably fixed thereto and into which the inner frame with the parts supported thereby may be introduced as a single unit and from which it may be so detached.
- 25 10. In a typewriting machine, the combination of a system of type actions, a carriage, a case shift frame therefor, carriage escapement mechanism, a universal bar, ribbon feed mechanism, an inner frame by which the hereinbefore mentioned parts are supported, and an outer frame enclosing said 30 inner frame and detachably fixed thereto and into which the inner frame with the parts supported thereby may be introduced as a single unit and from which it may be so detached.
- 35 11. In a typewriting machine, the combination of a system of type actions, a carriage, a case shift frame therefor, carriage escapement mechanism, ribbon mechanism including ribbon spools, ribbon feed devices, a ribbon vibrator, and actuating means for the ribbon vibrator, an inner frame by which the hereinbefore mentioned parts are supported, and an outer frame enclosing said 40 inner frame and detachably fixed thereto and into which the inner frame with the parts supported thereby may be introduced as a single unit and from which it may be so detached.
- 45 12. In a typewriting machine, the combination of a carriage, escapement mechanism therefor, a system of type actions having collapsible parts, means for collapsing and expanding the collapsible parts of said type actions, an inner frame on which the hereinbefore mentioned parts are supported, and
- an outer frame fixed to but detachable from and inclosing said inner frame and into 60 which the inner frame with the said parts supported thereby may be introduced as a single unit and from which it may be so detached.
13. In a typewriting machine, the combination of a system of type actions, a carriage, escapement mechanism therefor, ribbon mechanism, a system of type actions having collapsible parts, means for collapsing and expanding said collapsible parts, 70 an inner frame on which the hereinbefore mentioned parts are mounted, and an outer sheet metal frame fixed to but detachable from and inclosing said inner frame and into 75 which the inner frame with said parts supported thereby may be introduced as a single unit and from which it may be so detached.
14. In a typewriting machine, the combination of a system of type actions having collapsible parts, means for collapsing and 80 expanding said parts, an inner frame on which the system of type actions in their entirety and said means for expanding and contracting parts thereof are supported, and an outer frame fixed to but detachable from 85 and inclosing said inner frame and into which the inner frame with the said parts carried thereby may be introduced as a single unit and from which it may be so detached.
15. In a typewriting machine, the combination of an inner sheet metal frame which carries all of the working parts of the machine and includes in its construction a cross bar fixed to and uniting the sides of said 90 inner frame, and an outer sheet metal frame 95 in which the inner frame is contained and to which it is detachably fixed.
16. In a typewriting machine, the combination of an inner sheet metal frame which carries all of the working parts of the machine and includes in its construction a hollow sheet metal cross bar fixed to and uniting the sides of said inner frame, and an outer sheet metal frame in which the inner 100 frame is contained and to which it is detachably fixed, and from which the inner frame with the parts carried thereby may be detached as a single unit.

Signed at the borough of Manhattan, city of New York, in the county of New York 110 and State of New York this 5th day of May, A. D. 1922.

JOHN H. BARR.
